UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DESIGN FOR AN AUTOMOBILE.

49,746.

Specification for Design.

Patented Oct. 10, 1916.

Application filed July 19, 1916. Serial No. 110,242. Term of patent 14 years.

To all whom it may concern:

Be it known that I, JOSEPH LEDWINKA, a citizen of the United States, residing at Philadelphia, in the county of Philadelphia, State of Pennsylvania, have invented a new, original, and ornamental Design for Automobiles, of which the following is a specification, reference being had to the accompanying drawing, forming part thereof.

Figure 1 is a view in side elevation of an automobile showing my new design. Fig. 2 is a top plan view of the same.

I claim:

The ornamental design for an automobile, as shown.

In testimony whereof I have hereunto set my hand in the presence of the subscribing witnesses, on this 17th day of July, A. D. 1916.

JOSEPH LEDWINKA.

Witnesses:

A. H. BUxBAUM,
N. J. LEIDY.
